UNITED STATES PATENT OFFICE.

ALPHONSE KAMP, OF OSTEND, BELGIUM.

BOGIE FOR RAILWAY AND LIKE CARRIAGES.

Application filed June 19, 1923. Serial No. 646,359.

To all whom it may concern:

Be it known that I, ALPHONSE KAMP, engineer, a subject of the King of the Belgians, residing at Ostend, Belgium, 87 Chaussee de Nieuport, have invented a new and useful Improvement Relating to Bogies for Railway and like Carriages, of which the following is a specification.

The present invention relates to an improvement in bogies for railway and tramway carriages of the "Bissel" type, that is to say of the type wherein the centre of rotation of the bogie is not coaxial with the centre of figure of same, and the said invention has for its main object to devise a bogie of the type referred to which will ensure a better distribution of the load than is the case for the known constructions, and wherein any undesirable stresses will be avoided.

Most single axle bogies of the "Bissel" type are loaded in two points, that is to say at the centre of two blade springs arranged above the grease-boxes, and small links or connecting members suspended to the ends of the said springs tend to bring the bogie back to its initial position by pulling obliquely on the said springs, thereby putting an abnormal additional stress on same.

It has also been suggested to load such bogies in three nonelastic points, but in such cases the two rods which were provided to bring the bogie back to its initial position were not arranged in a rational manner and the said construction has therefore not given satisfaction.

It has further been proposed to construct bogies of the "Bissel" type adapted to be brought back to their initial position by means of four connecting members of equal length of which two were placed nearer to the centre of rotation than the two others, whereby the more distant of the said connecting members were subjected to a greater movement so that their reaction was more violent than that of the two other connecting members.

The present invention comprises a bogie of the "Bissel" type loaded in three elastic points and which is adapted to be brought back to its initial position by means of two rod connections of particular construction.

In order that the invention may be more readily understood, one embodiment of same is, by way of example only, illustrated by the accompanying drawing, wherein:

Fig. 1 is a longitudinal elevation showing a carriage frame provided with a pair of bogies in accordance with the invention;

Figs. 2 and 3 are respectively a corresponding plan view and a corresponding end view, and

Figs. 4 and 5 are two different detail views of one end of one of the rod connections provided according to the invention to bring the bogies back in their initial position.

As may be seen from the drawing, the bogie according to the invention comprises a bogie frame C which in the embodiment illustrated surrounds the wheels. The carriage frame carrying the body of the carriage is supported on two similar bogies of the "Bissel" type and each of the said bogies is loaded in three points of which one S is the centre of rotation of the bogie and is situated on the longitudinal axis of the carriage frame towards the centre of same. The corresponding end of the bogie frame is at this point, that is in its centre, provided with a spherical socket adapted to receive the spherical lower end of a vertical pivot pin E able to slide vertically within a guide piece G secured to the carriage frame, the load at this point being transmitted through the medium of a single or compound spring R. The load is moreover transmitted to the bogie in two points P positioned symmetrically in relation to the longitudinal axis and towards the end of the carriage frame.

At each of these two points the load is transmitted by means of a rod connection B of which the upper end bears by means of

a ball and socket joint on a spring R' which itself bears on the corresponding end of the bogie frame C and is located in a box b secured to the said bogie frame C, while the lower end of the said rod connection B carries a suitable bracket secured to the corresponding point of the carriage frame.

The lower end of the rod connection B might be fitted with a single pin only, but if it is desired to obtain an initial return to the normal position, it is necessary to provide the said lower end with two parallel pins t situated on the same horizontal axis.

Besides, as the movements of the lower end of the rod connections B about the centre of rotation S do not take place in a straight line, the two pins t support the carriage frame through the medium of an intermediate piece I which is itself capable of oscillation about the axis of a pair of knives c provided on the brackets secured to the carriage frame and arranged with their said axis at right angles to the pins t. The bogie has, besides, the ordinary suspension of carriages, the said suspension comprising in the embodiment shown two blade springs passing under the grease boxes and reaction springs CR connecting the bogie frame C to the end of the said blade springs, which always work under normal stress, considering that in the transverse direction the grease boxes are rigid in relation to the bogie frame.

The operation of the above described bogie will be easily understood. Under the action of centrifugal force, the carriage frame carrying the carriage body will exert a radial pressure towards the outside of the curve. The points S of the bogies being kept in position in relation to the carriage frame, are thrown in an outward direction in relation to the curve, and the bogie frames are thus compelled to pivot about the said points and to take a position in which their own longitudinal axis forms at the points S an angle with the longitudinal axis of the carriage frame, i. e. extends for instance as indicated by the dot and dash lines starting at S and ending at X Fig. 2.

These movements, however, are controlled by the rod connections B which, being self-reacting owing to the knife- and double-pin bearings through which the load is transmitted to them, tend to bring the longitudinal axes of the bogies back to the position in which they are coaxial with the longitudinal axis of the carriage frame as soon as the latter ceases to be subjected to the effort in a transverse direction.

Experiments have shown that the two bogies do not always move in unison in relation to the direction of the curve, and therefore they are connected by means of

a diagonal connecting rod T which compels them to act in unison.

In the embodiment shown the two pins t are provided on the lower end of the rod connections B, but it is of course obvious that they may just as well be provided on the upper end of the said rod connections. Further, these pins are in the embodiment illustrated secured on the rod connections B themselves but it should be understood that they may also be provided on the bogie frames or on the brackets secured to the carriage frame, or even on the intermediate piece between the said brackets and the corresponding end of the rod connections. Similarly, it is obvious that the two knives about which the said intermediate piece is able to oscillate may if desired be replaced by one or two pins.

I claim:

1. In a bogie for railway and tramway carriages, of the type wherein the centre of rotation is not coaxial with the centre of figure of the bogie structure, the combination of a bogie-frame, a sphere-ended vertical pivot-pin bearing on the centre of the transverse member of the said bogie-frame nearest the centre of the carriage so as to form the turning centre of said bogie-frame, and resiliently supporting the carriage frame at a point situated on the longitudinal axis thereof, and two self-reacting universally-movable rod connections bearing on two points of the other transverse member of the bogie-frame and resiliently supporting the carriage frame at two points situated symmetrically in relation to the longitudinal axis of said frame and nearer to the end thereof than its point of support by the aforesaid pivot-pin, substantially as described.

2. In a bogie for railway and tramway carriages, of the type wherein the centre of rotation is not coaxial with the centre of figure of the bogie structure, the combination of a bogie-frame, a sphere-ended vertical pivot-pin bearing on the centre of the transverse member of the said bogie-frame nearest the centre of the carriage so as to

form the turning centre of said bogie-frame, and resiliently supporting the carriage frame at a point situated on the longitudinal axis thereof, and two self-reacting universally-movable rod connections bearing on two points of the other transverse member of the bogie-frame and resiliently supporting the carriage frame at two points situated symmetrically in relation to the longitudinal axis of said frame, and nearer to the end thereof than its point of support by the aforesaid pivot-pin, said rod connections having the joints at their ends formed on the one hand by a ball and socket arrangement and on the other hand by a pair of parallel pins provided on the cor-

responding end of said rod connections and arranged to cooperate with an intermediate knife bearing in such a manner to allow the oscillation of said rod connections about 5 two axes at right angles to each other.

3. In a combination of two bogies as claimed in claim 1, the provision of at least one diagonal connecting-rod extending between and pivotally connected to opposite

corners of the corresponding ends of the 10 two bogie-frames.

In testimony whereof I signed hereunto my name in the presence of two subscribing witnesses.

ALPHONSE KAMP.
